UNITED STATES PATENT OFFICE

JOHN W. MCKINLEY, OF PAWTUCKET, RHODE ISLAND, ASSIGNOR TO UNITED STATES FINISHING COMPANY, OF NEW YORK, N. Y., A CORPORATION OF CONNECTICUT

PILING MACHINE

Application filed March 28, 1929. Serial No. 350,484.

This invention relates to a piling machine primarily intended to be utilized in connection with disposing cloth and similar materials in bins, the present invention providing a machine of this nature embodying structurally and functionally improved characteristics.

It is an object of the invention to construct an apparatus of this type in which the danger 10 of the material operated upon becoming contaminated with grease or other injurious substances is reduced to a minimum.

A further object of the invention is that 15 of providing a cloth piling machine which, when desired, may be shifted freely from one bin to another and with practically no danger of the parts becoming jammed.

A still further object is that of constructing 20 a machine in which the relative speed of movements of the several operating parts may be varied in order to insure exactly the result desired.

Another object is that of furnishing an 25 apparatus of this nature, the parts of which will be relatively few in number and individually simple and rugged in construction, these parts being capable of ready assemblage and when so assembled operating over long 30 periods of time with freedom from mechanical difficulties.

With these and other objects in mind, reference is had to the attached sheets of drawings, illustrating a practical embodiment of the invention and in which:

35 Figure 1 is a side elevation of the piling apparatus;

Fig. 2 is a front end view thereof, and

Fig. 3 is a plan view.

40 In these views, the numeral 10 indicates a main structural supporting frame carrying tracks 11 extending over the several bins (not shown) and with which the apparatus is to cooperate. Riding upon these tracks is a

45 carriage 12 supported by axles 13 carrying rollers 14 which bear against the tracks, and one axle may be extended to mount a gear 15, the teeth of which mesh with those of a rack 16 extending adjacent to one of the tracks.

50 Any suitable mechanism may be employed to drive the rollers 14. For example, the ex-

tension of the axle may carry a sprocket wheel 17 over which a chain 18 passes. This chain conveniently extends to a point easily accessible to the operator and it is obvious that by this construction the entire frame of 55 the carriage 12 may be shifted readily along the tracks from one bin to another. Thus, the probability of the apparatus becoming jammed in being transferred is reduced to a minimum—and additionally, in the event 60 that manual actuation of the chain or axle is resorted to—a single operator may readily effect such shifting.

The carriage includes sill members, the 65 upper edges of which define track portions 19 upon which there is supported the carriage proper 20 of the apparatus, by means of rollers 21 mounted upon axles 22. This carriage supports adjacent each of its ends 70 motors 23 and 24 and the latter, by means of a worm and wheel assembly 25, drives a shaft 26 mounted upon bracket 27 and having, as shown in Figs. 1 and 2, a right and left hand thread or screw 28. Mounted upon this portion of the shaft is a traveler 29 suitably 75 engaging the screw and formed with a pot eye 30 through which the material to be piled passes. It is obvious that this element under continued rotation of the shaft 26 will be caused to reciprocate along this shaft, thus 80 producing the result desired. The shaft 26 additionally carries a sprocket 31 or other suitable drive serving by means of, for example, a chain 32 to drive a reel shaft.

85 As shown, this reel may include an annular series of radially extending arms 33, carrying contact portions 34 for frictional engagement with the rope of material 35 and it will be apparent that as the traveler and pot eye reciprocate along the shaft 26 the material compacted by this structure will be drawn over the reel incident to the provision of the drive 31—32.

90 The motor 23 is connected by means of leads (not shown) to a reversing switch disposed within the casing 36. This motor is of the reversing type and the switch is operated by a trigger 37 acting in conjunction with limit stops 38 affixed to the frame 12. Thus, it will be apparent that as the carriage 95 100

20 is reciprocated along the track portions 19 the reversing switch will be caused to operate periodically, this resulting in a reversal of movement on the part of the motor 23.

3 This motor drives a worm and wheel 39 the latter serving to actuate a sprocket driving a chain 40 connected to a second sprocket wheel affixed to the axle or shaft 22. Thus, it will be apparent that the motor will reciprocate in its operation the entire carriage. 20 This movement, in conjunction with the actuation of the pot eye and reel will serve to pile the material within the bin or other receptacle.

13 Both motors are connected to a source of current supply by means of, for example, a power cable 41 passing over rollers 42 and which extends, for example, to an outlet box 43 containing an automatically acting "take 20 up" drum or reel 44 so that at no time will there be any slack in the cable. Thus, it will be apparent that by the provision of a single switch, the flow of current to both motors may be interrupted so that the machine may 25 instantly be stopped when necessary.

It will be appreciated that the reciprocation of the carriage is usually relatively slow with respect to the movements of the pot eye. However, incident to providing two motors, it will be obvious that their operation may be adjusted in order to vary this ratio in any manner desired. Moreover, by providing two motors, it is entirely practicable to eliminate the cumbersome clutches, gears, 35 etc., which have heretofore been employed in order to achieve the several necessary movements. Also, the motors, by being positioned adjacent opposite sides of the carriage, will balance each other, thus assuring an even 40 traction, resulting in smoother operation and permitting of a design which is extremely compact.

Thus, it will be appreciated that, among others, the several objects specifically afore 45 referred to are achieved. It will, moreover, be apparent that roller and/or other suitable friction bearings are preferably employed throughout the entire apparatus. Also, one or both of the motors has any desirable control for varying the speed there- 50 of so that the relative speeds of operation of these motors may be adjusted to produce a harmonious and desirable result. These bearings and speed controls have not been 55 shown in that they will be readily apparent to anyone skilled in the art and to illustrate them would serve no useful purpose. In conclusion it will be apparent that numerous changes in construction and rearrangement 60 of the parts might be resorted to without departing from the spirit of the invention as defined in the claims.

Having described my invention, what I claim as new and desire to secure by Letters 65 Patent is:—

1. A piling machine including a carriage, rails for mounting said carriage, means for reciprocating said carriage along said rails, a pot eye associated with said carriage and to be reciprocated with respect thereto, 70 means for operating said carriage and pot eye, a further carriage forming a part of said track members, rollers mounting said latter carriage, tracks for supporting said rollers and a manually operated drive connected to one of said rollers for shifting said latter carriage along said tracks. 75

2. A piling machine including a carriage, rails for mounting said carriage, means for reciprocating said carriage along said rails, 80 a pot eye associated with said carriage and to be reciprocated with respect thereto, means for operating said carriage and pot eye, a further carriage forming a part of said track members, rollers mounting said latter carriage, additional tracks for supporting said rollers, and further means associated with 85 said rollers for shifting said latter carriage along said last named tracks.

3. A piling machine including, in combination, a shiftable frame, a pot eye mounted on said frame and adapted for reciprocating movement transversely of the movement of said frame, a plurality of rails supporting 95 said frame for reciprocating movement, bearing surfaces carried by said rails, secondary rail members cooperating with said bearing surfaces to effect a progressive movement of said frame and first named rails in the direction of travel of said pot eye, and means for 100 producing movement of the parts.

4. A piling machine including a shiftable frame, rails mounting said frame, means for effecting reciprocal movement of said frame on said rails, a pot eye carried by said frame, 105 means for effecting further reciprocal movement of said pot eye transversely of the path of travel of said frame, bearing surfaces carried by said rails, secondary rail members cooperating with said bearing surfaces whereby 110 said frame and first named rail members may be progressively advanced in the direction of the path of travel of said pot eye, and additional means for effecting said last named 115 movement.

In testimony whereof I affix my signature.
JOHN W. McKINLEY.
